(57) **CLAIM**

The ornamental design for a combination portable toilet and trash receptacle, as shown and described.

DESCRIPTION

FIG. 1 is a top perspective view of a combination portable toilet and trash receptacle, showing my new design;

FIG. 2 is a front elevation view thereof;

FIG. 3 is a rear elevation view thereof;

FIG. 4 is a top plan view thereof;

FIG. 5 is a left-side elevation view thereof;

FIG. 6 is a right-side elevation view thereof;

FIG. 7 is a top perspective thereof, shown in a first used condition; and,

FIG. 8 is a top perspective thereof, shown in a second used condition.

The alternating sized broken lines depict the bounds of the combination portable toilet and trash receptacle; the alternating sized broken lines form no part of the claimed design. The broken lines shown in FIGS. 7 and 8 depict environmental subject matter that forms no part of the claimed design.

1 Claim, 8 Drawing Sheets
